[57] CLAIM

The ornamental design for a stackable composite package, as shown and described.

DESCRIPTION

FIG. 1 is a perspective view of a stackable composite package showing our new design;

FIG. 2 is a front elevational view;

FIG. 3 is a side elevational view, the opposite side being a mirror image;

FIG. 4 is a top plan view;

FIG. 5 is a rear elevational view;

FIG. 6 is a bottom plan view; and,

FIG. 7 is a top perspective view of a blank for forming an outer sleeve portion.

The broken line showing of the internal containers is for illustrative purposes only and forms no part of the claimed design.
